[57] ABSTRACT

A method and apparatus is disclosed for using a plurality of spaced sequential induction circuits for inducing a predetermined current distribution pattern in a localized segment of a filament. The induced current pattern is controlled by combining the effects of electromagnetic induction, and standing wave patterns on the filamentary conductor together with the transmission attenuation along the filamentary conductor. Additionally, the effect of the configuration of an induction circuit on induced current is covered.

LOCALIZED HEATING FILAMENTS BY INDUCED CURRENTS

The theory and mechanism of heating filaments by means of induction currents is well known and fully documented in the specification and file wrapper of U.S. Pat. No. 3,607,603. The disclosure in this patent relating to the effect of high electric fields on induced currents in the filament is pertinent.

In the previously identified patent, U.S. Pat. No. 3,607,603, a filament is passed through the high voltage (high electric field) region of the RF field and heated. In the apparatus described in the patent, a very limited region of the filament is heated. Additionally, there is no provision for providing localized heating at selected regions along the filament. Further, the patented configuration includes no provision for shaping the induced current distribution along the filament length.

Though in one respect this invention operates in a manner similar to the patented invention, this invention concept avoids limitations discussed just above.

Though the preferred embodiment relates to auxiliary localized heating where the primary heat source is DC or utility AC power, the invention concept may be used as the principal heat source. The latter procedures will depend largely on economics.

The invention has particular application to the manufacture of high-strength and high modulus carbon, boron and silicon carbide filaments, for example.

It is an object of the invention to provide a method and apparatus for providing localized heating of filaments which avoids the limitations and disadvantages of prior inventions and apparatus.

It is another object of the invention to provide a method and apparatus for providing localized heating of filaments by combining the effects of induced currents produced by two or more induction circuits.

It is still another object of the invention to provide a means for inducing a predetermined current distribution pattern in a localized segment of a filament.

It is yet another object of the invention to control induced current distribution patterns by combining the effects of electro-magnetic induction and standing wave patterns on the filamentary conductor.

It is yet another object of the invention to disclose a means for modifying an induced current distribution pattern by modifying the configuration of the induction circuit.

A method of resistance heating a filament comprises the steps of establishing at least a pair of induction circuits, each of which induces current in a filament. The induced currents interact to form predetermined current distribution patterns.

The novel features that are considered characteristic of the invention are set forth in the appended claims; the invention itself, however, both as to its organization and method of operation, together with additional objects and advantages thereof, will best be understood from the following description of a specific embodiment when read in conjunction with the accompanying drawings, in which:

FIG. 1 is a schematic representation of an apparatus for manufacture of high modulus filaments which embodies the principal of the present invention; and

FIGS. 2A through 2C are idealized schematic representations of an alternate apparatus configuration.

Referring to FIG. 1, there is shown a schematic representation of a reactor 10 of the type used for depositing a coating upon a substrate such as is used in making boron filament or silicon carbide filament. Conventionally, a filamentary substrate such as tungsten, molybdenum, or carbon wire is supplied by means of a reel 11 through an electrical contact 12 and passes through the length of the reactor 10 to a second electrical contact 13 to a take-up reel 14.

Typically, the coating material is obtained by thermally decomposing a gas flowing through the reactor 10. The gas enters by way of conduit 16, passes through the reactor and out through a conduit 17 to a recovery system to be recycled. In the event boron is to be deposited on the filament substrate, the gas is a boron halide, generally boron trichloride. Where silicon carbide is to be deposited, an alkyl silane is generally used. These gases are also generally mixed with hydrogen to provide a reducing atmosphere.

Similarly, TiB₂ may be deposited from TiCl₄ and BC₁₃ with hydrogen; or B₄C from BC₁₃ with a hydrocarbon or BN from BC₁₃ and trichloroborazole. The localized heating should also work in reactors designed for depositing TaC₄ and TiC from a vapor phase or for converting a carbon filament into a high modulus graphite filament.

Typically, the substrate filament 18 is heated by passing DC current through the filament by means of contacts 12 and 13. The substrate filament is heated to a temperature which is sufficient to cause the reagent gas to decompose and deposit a coating on the surface of the substrate; boron or silicon carbide for the gases specified.

A very serious problem associated with the basic coating technique just described is that the resistance per unit length of the filament varies with the length because the amount of material deposited—the thickness of the coating—on the substrate filament increases as the substrate filament passes through the reactor. As a result, the filament temperature varies as a function of distance through the reactor. Most often the temperature falls off more rapidly than desired as the filament passes through the reactor. Frequently localized heating is sought to make the temperature profile more nearly constant. Temperature control may be obtained by cooling normally hotter regions, or conversely, heat can be supplied to a cooler region to bring the temperature up. The subject of this invention is directed to such auxiliary heating by means of inducing current in the filament, and, in particular, to localized auxiliary heating.

Referring to FIG. 1, there is shown a number of induction circuits along the length of the filament 18. Each induction circuit induces a current in a localized region of the filament by electromagnetic induction. Preferably, the induction circuits are supplied with VHF energy in the 10 mhz to 100 mhz range, for example.

Induction circuit 21 comprises an L-shaped wire inductance 22 connected in series with a capacitor 23. The wall 24 of the reactor 10 is an RF ground, as indicated. Typically, the induction circuit 21 is coupled to a source of VHF energy (not shown) by means of the coupling means 26. Preferably, the series inductance 22 and the capacitor 23 will comprise a tuned circuit, usually a quarter wave tuned circuit, for maximum efficiency.

One leg 27 of the inductance 22 extends parallel and is spaced from the substrate filament 18. The terminal end 29 preferably, but any point along the inductance of the leg 27 is connected to the capacitor 23. The opposite end of the leg 27 terminates in the corner of the L-shaped inductance 22. The terminal end 29 is a high electric field region. The electromagnetic field is coupled to the substrate filament 18 and induces within the substrate filament 18 a localized current in the region of the substrate filament 18 adjacent to the terminal end 29. The electric field gradient is generally axially disposed so that, in this case, the current induced in the substrate filament 18 is axial.

The strength of the electric field at the corner of leg 27 is somewhat less than at the terminal end 29. As one would expect, current in the inductance at the corner of leg 27 is somewhat higher; the current is maximum at the terminal end 30 of leg 27. The electromagnetic field in the vicinity of the corner induces a current in the substrate filament 18 in the region opposite the corner.

A graphical representation of the currents induced by the several induction circuits shown in FIG. 1 is illustrated by a plurality of curves. The curves represent the magnitude of current as a function of length along the substrate filament 18, as indicated.

The current maximum 32 and 33 arise because of the change in transmission characteristics of the conducting filament 18 as a result of the proximity of the conductor of the tuned circuit. Within the region near the tuned circuit, the characteristic impedance of the conducting filament 18 is lower than it is outside this region. At this point of discontinuity, the standing wave current distribution is altered by wave reflections at the discontinuity, in the higher impedance sections outside the tuned circuit. The reflection reinforces the oncoming wave, and in the lower impedance region within the coupling loop, the reflection at the discontinuity is out of phase with the main induced wave. As a result, a current maximum occurs outside the region where the tuned coupling loop is located.

Curve 31 represents the current distribution induced in the substrate filament 18 by the tuned circuit 21. The small peak 32 is adjacent the corner leg 27. The large peak is opposite the terminal end 29. The relative magnitudes of the peaks 32 and 33 will vary, particularly as the length of the leg 27 is changed.

The next region of interest comprises a tuned circuit 41 and an adjacent loop 42. Curve 43 represents the current distribution in the selected region in the substrate filament derived from the tuned circuit 41. Curve 44 represents the current distribution in the substrate filament generated by the loop 42. The loop 42 produces a predominantly electromagnetic field. Since the loop 42 is not coupled to the VHF supply means, the energy contained in loop 42 is derived from energy coupled to loop 42 from the tuned circuit 41. A single current peak 44 is derived from the loop 42. Curve 46 is composite representing the actual current distribution in the region caused by the combined effects of curves 43 and 44. Further down the reactor 10 are three tuned circuits 51, 52 and 53. Current distribution 54 is generated by tuned circuit 51. Current distribution 56 is generated by tuned circuit 52. And, current distribution 57 is generated by tuned circuit 53. Curve 59 is the composite actual current distribution in the substrate filament 18 in the specific region generated

by the combined effects of the current distributions 54, 56 and 57.

In principle, one could obtain as nearly as desired to a predetermined current distribution by using a multiplicity of tuned coupling circuits, each as short as necessary to keep the variation of current along the filament to be heated as desired. In practice, however, these closely spaced tuned circuits also couple with each other as well as with the filament to be heated, making difficult the task of tuning the group of tuned circuits. A method to reduce the complexity of multiple coupling loops is shown in tuned circuit 53 where the leg 58 is bent with a concave portion 60. The portion of the tuned circuit bent away from the heated filament causes reflections exactly the same as those beyond the ends, causing an additional current maximum within the tuned circuit region. By using this additional feature of perturbing the shape of each tuned circuit, one can obtain the same effect with fewer (perturbed) tuned circuits as could be obtained with many more shorter unperturbed units.

Conceptually therefore, a means is provided for modifying the normal current distribution patterns of tuned circuits by altering the configuration of the inductance of the tuned circuit in the region running parallel with the filament to be heated. Referring to curve 59 and particularly the region between tuned circuits 51 and 52, it is seen that the curve drops, typically, to a low level of current in the region between points C and D. Because the magnitude of current represented by curve 54 and 56 falls off rapidly between A and B.

On the other hand, the effect of the double peaks 61 and 62 in curve 57 providing a heated boost in current in the region between points C and D tending to develop a current plateau in that region of the composite curve 59. The dotted curve 60 represents the drop in current that would have occurred in the absence of C.

FIG. 2 contains schematic representations of placing a pair of tuned circuits side-by-side with their respective predominantly high voltage regions in an adjacent relationship. In FIG. 1, a high electric field region was located next to a region of lesser electric field. In FIG. 2, the current induced with a substrate filament results primarily from the interaction of the adjacent high electric fields. Curve 71 is generated by tuned circuit 72. Curve 73 is generated by tuned circuit 74. Current circuit 75 is the composite of 71 and 73. Note that current curve 75 is a single relatively sharp peak.

In FIG. 2b the tuned circuits 76 and 77 are spaced further apart than their counterparts in FIG. 2a. The composite current curve 81 represents the combined effects of the individual curves 82 and 83 and a single peak. Significant is that this peak is more rounded off than the peak in the composite curve 75.

Where the tuned circuits are even more widely spaced as shown in FIG. 2c, the composite current distribution curve 84 contains a plurality of peaks, and extends over a greater length of the substrate filament 18.

The various features and advantages of the invention are thought to be clear from the foregoing description. Various other features and advantages not specifically enumerated will undoubtedly occur to those versed in the art, as likewise will many variations and modifications of the preferred embodiment illustrated, all of which may be achieved without departing from the spirit and scope of the invention as defined by the following claims.

I claim:

1. Means for inducing a predetermined point to point current distribution in a localized segment of a filament comprising:

at least a pair of induction circuits disposed in a spaced relationship along the length of said filament, each of said induction circuits inducing localized current in a localized region of said filament, said localized currents interacting to produce a predetermined composite current distribution.

2. Means for inducing a predetermined point to point current distribution in a localized segment of a filament as defined in claim 1 wherein said induction circuits consist essentially of tuned circuits, as loops, modified tuned circuits, modified loops or combinations thereof.

3. Means for inducing a predetermined point to point current distribution in a localized segment of a filament as defined in claim 1 wherein at least one of said induction means produces axially spaced impedance discontinuities, said discontinuities inducing currents having standing waves that generate axially spaced current peaks in said filament in a localized region opposite each discontinuity.

4. Means for inducing a predetermined point to point current distribution in a localized segment of a filament as defined in claim 3 wherein said one induction circuit is a tuned circuit.

5. Means for inducing a predetermined point to point current distribution in a localized segment of a filament as defined in claim 3 wherein said tuned circuit comprises an L-shaped inductance with one leg of the inductance extending parallel to said filament, the terminal end and the corner of said one leg causing impedance discontinuities.

6. Means for inducing a predetermined point to point current distribution in a localized segment of a filament as defined in claim 5 wherein the spacing between said one leg and said filament is varied to induce additional localized impedance discontinuities in the region of said filament between the terminal end and said corner.

7. Means for inducing a predetermined point to point current distribution in a localized segment of a filament as defined in claim 3 wherein adjacent induction means inducing currents are disposed with the maximum electric field of one induction circuit positioned adjacent to a region of lesser electric field of another induction circuit.

8. Means for inducing a predetermined point to point

current distribution in a localized segment of a filament as defined in claim 3 wherein adjacent induction means inducing currents are disposed with the region of maximum electric field of one induction circuit positioned adjacent to the region of maximum electric field of another induction circuit.

9. A method of heating a filament comprising the steps of:

inducing a predetermined point to point localized current in a localized region of said filament by the combination of electromagnetic induction and the introduction of axially spaced impedance discontinuities by at least two induction circuits consisting essentially of tuned circuits, as loops, modified tuned circuits, modified loops or combination thereof.

10. In a method whereby a carbon filament is heated near or at graphitizing temperatures, the improvement comprising supplying localized heat by inducing two or more axially spaced and predetermined point to point localized currents in a localized region of the carbon filament to add heat to said carbon filament locally.

11. A method of making a high-strength high-modulus filament comprising the steps of:

- providing a substrate filament into which currents can be induced;
- drawing the substrate filament through a reactor containing vapors which react at elevated temperatures to deposit boron or SiC on a heated substrate, said filaments being heated along its entire length by a first source of heat; and
- supplying localized heat by inducing two or more axially spaced and localized currents in a localized region of the substrate filament.

12. A method of making a high-strength high-modulus filament comprising the steps of:

- providing a substrate filament into which currents can be induced;
- drawing the substrate filament through a reactor containing vapors which react at elevated temperatures to deposit a coating taken from the class consisting essentially of TiB₂, B₄C, BN, TiC or TaC₄ on a heated substrate, said filaments being heated along its entire length by a first source of heat; and
- supplying localized heat by inducing two or more axially spaced and localized currents in a localized region of the substrate filament.
